UNITED STATES PATENT OFFICE.

FRANK A. DONALDSON, OF MINNEAPOLIS, MINNESOTA.

AIR CLEANER.

Application filed August 31, 1923. Serial No. 660,412.

To all whom it may concern:

Be it known that I, FRANK A. DONALDSON, a citizen of the United States, residing at Minneapolis, in the county of Hennepin and State of Minnesota, have invented certain new and useful Improvements in Air Cleaners; and I do hereby declare the following to be a full, clear, and exact description of the invention, such as will enable others skilled in the art to which it appertains to make and use the same.

My present invention relates to air cleaners for use in connection with carburetors of internal combustion engines and, generally stated, the invention consists of the novel devices and combinations of devices herein-after described and defined in the claims. Certain of the features herein disclosed are also disclosed and more broadly claimed in my pending application, Serial No. 514,628, filed of date November 12, 1921, and in the division of said application, filed of date Aug. 31, 1923, under Serial No. 660,411.

In the accompanying drawings, which illustrate the invention, like characters indicate like parts throughout the several views.

Referring to the drawings:

Fig. 1 is a side elevation showing one of my improved air cleaners applied to an internal combustion engine and connected to the air intake of the carburetor of said engine;

Fig. 2 is a horizontal section taken on the line 2—2 of Fig. 1;

Fig. 3 is a vertical section taken on the line 3—3 of Fig. 2;

Fig. 4 is a vertical axial section illustrating a modified form of the air cleaner; and

Fig. 5 is a horizontal section taken on the line 5—5 of Fig. 4.

The construction illustrated in Figs. 1, 2 and 3 will first be described. The engine diagrammatically illustrated in Fig. 1 is or may be assumed to be of the Ford type, the said engine being indicated as an entirety by the numeral 6 and its intake and exhaust manifolds, respectively, by the numerals 7 and 8. The carburetor, which is of the usual or any suitable construction and is connected in the customary way to the intake manifold 7, is indicated by the numeral 9.

The air cleaner here illustrated comprises

a horizontally disposed cylindrical outer shell 10 that is provided with heads 11 and 12 applied to the ends thereof with slight telescopic engagement. The head 11, as shown, is dished inward and provided with an outstanding axial sleeve 13 that affords an air discharge port from the air cleaner and is connected to the air intake passage of the carburetor 9 by an air tube 14 shown as of the flexible jointed type. An annular neck 15, shown as provided with pressed metal threads, has an outstanding flange that is soldered or otherwise rigidly secured to the head 11.

Located within the shell 10, spaced therefrom, and extended axially thereof, is a perforated tube 16 preferably in the form of a truncated cone and having at its small end a head that is rigidly but detachably secured to the head 12 by a nut-equipped bolt 17. Rigidly secured to the large end of the tube 16 is an annular collar 18, preferably of sheet metal, formed with an outwardly and backwardly extended flange 19 that affords a seat to receive one end of a cylindrical wire screen 20, the other end of which screen is pressed against the head 12. Soldered or otherwise rigidly secured within the collar 18 is a collar 18^a that is formed with pressed threads adapting it to be screwed onto the neck 15.

The air cleaner above described may be operated in any suitable position, but for application to engines of the Ford type, it is advisably horizontally disposed and secured closely adjacent to or against the exhaust manifold 8 by a saddle bracket 22, which latter, as shown, is anchored to said manifold by nut-equipped studs 23. The outer shell 10 is provided with air intake ports 24 advisably located on the under side thereof quite close to the exhaust manifold 8, so that the air drawn into the shell, to be cleaned and thereafter to be delivered to the carburetor, will be more or less preheated by heat radiated from said exhaust manifold.

In the operation of the engine, suction produced through the carburetor in the customary way will produce a partial vacuum in the perforated inner tube 16, so that air will be drawn in through the air intake ports 24, distributed around the screen 20 and fil-

tering material 21, and thence drawn in through the said filtering material to the interior of the tube 16. As is evident, only clean air will reach the interior of the tube 16 and this clean air will be drawn to the carburetor through the air tube 14. Moreover, this clean air will be preheated to a considerable extent by heat radiated from the exhaust manifold, as above noted, and 10 further by heat conducted to the interior of the shell 10. When the filtering material has become too much loaded with collected dust, it may be readily removed, quickly cleaned in gasoline and replaced in working position. To perform the actions just noted, the head 12 will be rotated, thereby rotating therewith the perforated tube 16 and the threaded collar 18, so that the latter will be 15 screwed off from the threaded neck 15. 20 When the said threaded elements are disengaged, the head 12, tube 16 and parts connected thereto, including the screen 20 and filtering material 21, may be removed from the relatively fixed outer shell 10 and from 25 the head 11 and its neck 15. The said head 11 is preferably clinched onto the end of the shell 10.

When the said parts are removed from the shell, as just noted, the filtering material 30 may be cleaned by dipping in gasoline, without separation of any of the elements 12, 16, 20 and 21; but if, at any time, it becomes necessary or desirable to remove the filtering material and to supply new material, it is 35 only necessary to remove the nut or bolt 17, which immediately disconnects said elements. It is important to note that the annular space between the perforated or reticulate sleeve 16 and cylindrical screen 20 tapers in longitudinal cross section from the filling toward 40 the opposite end of such space, that is, in a direction away from the head 12. This greatly facilitates the tight and proper packing of the filtering material between the said elements.

The air cleaner described has been found highly efficient for the purposes had in view and, at the same time, it is of small manufacturing cost.

50 The air cleaning device illustrated in Figs. 4 and 5 involves much of the construction illustrated in Figs. 1, 2 and 3. The elements 11, 13, 15, 16, 17, 18, 19 and 20 are, as illustrated, of the identical construction already described, except that they are placed 55 on a vertical rather than a horizontal axis. In this arrangement, the head 12^a, which corresponds to the head 12, is telescoped only onto the lower end of the cylindrical screen 60 20; and the cylindrical outer shell 10^a, which is here set upright, is, at its lower end, connected to the upper end of a funnel-like shell 25; and the said shell 10^a, at its lower portion, has a plurality of circumferentially 65 spaced air intake ports 26 formed by press-

ing the portions 27 inward with inclinations in a common circumferential direction. The funnel 25 is shown as provided below the head 12^a with a baffle plate 28 having circumferential air passages 29. On its external surface, the funnel 25 is provided with an annular neck 30 formed with pressed metal threads that engage the pressed metal threads of a collar 31 secured to the upper end of an air chamber 32 that surrounds the neck or lower discharge end of the funnel. This air chamber 32 is provided with a depending nozzle 33 and with a lateral air intake pipe 34, which latter, in practice, will be connected to the exhaust pipe of the engine. The clean air discharge neck 13 of this air cleaner, as in the structure previously described, will, of course, be connected to the air intake of the carburetor.

With this modified construction just described, the air drawn in through the air intake ports 26 will be caused to whirl or take up a whirling motion within the shell 10^a and around the filter. Under this whirling action, the heavier particles, such as dust, will be mostly thrown outward and precipitated into the hopper 25 and from thence delivered downward. The forced blast produced by the exhaust, downward through the nozzle 33, will produce a suction in the spout of the funnel 25, which will draw downward the precipitated dust and accelerate its delivery from the hopper 25 and from the shell 10^a.

What I claim is:

1. An air cleaner comprising an outer casing having a peripheral tangential air intake and an axial air discharge passage, a tubular filter inserted into said casing with its interior connected to said discharge passage and with its exterior directly exposed substantially in line with the axis of said intake to the air drawn into the casing through said air intake passage.

2. The structure defined in claim 1 in which said air intake passage is combined with means operative to cause the air passed therethrough to take a whirling motion around the exterior surface of said filter.

3. An air cleaner comprising an outer casing having an air intake passage and provided with heads, one of which is removable and one of which is provided with an air discharge passage, a tubular filter detachably connected to the head having said discharge passage, by means of screw-threaded engagement, and connected to rotate with the other head of said casing.

4. An air cleaner comprising an outer casing having air intake means and provided with a head having an air discharge passage and a threaded neck, and a tubular filter comprising spaced perforate tubular members and intervening fibrous filtering material, the inner tubular member having threaded en-

gagement with said threaded neck, and a head secured to the extended ends of said perforate tubular members and rotatable therewith.

5. The structure defined in claim 4 in which said latter noted head also forms a head to close one end of said outer casing.

6. The structure defined in claim 4 in which the annular space between said inner and outer perforate tubular members increases in cross section toward the said head, by means of which the filter may be rotated.

In testimony whereof I affix my signature.

FRANK A. DONALDSON.
